UNITED STATES PATENT OFFICE.

ALBERT MISRACHI, OF MEXICO, MEXICO.

DISPLAY AND STORAGE RACK.

Application filed September 3, 1926. Serial No. 133,369.

This invention relates to an improved storage and display rack suitable as an article of store furniture, and has more particular reference to a rack of this kind for the storage and display of magazines, books, and the like.

A specific object of the invention is to provide a rack including a plurality of shelves upon which magazines or books may be stored in piles, the shelves being cooperatively constructed for effectively supporting copies of the magazines or books in a substantially upright position at the front of the shelves so that a copy of the magazines or books composing such piles may be displayed to view in front of the latter.

A specific object is to provide a combined storage and display rack of the above kind which is extremely simple and durable in construction as well as efficient in use.

Other objects will become apparent as the nature of the invention is better understood, and the same consists in the novel form, combination, and arrangement of parts herein-after more fully described, shown in the accompanying drawing, and claimed.

In the drawing, wherein like reference characters indicate corresponding parts throughout the several views,

Fig. 1 is a fragmentary front elevational view of a multiple storage and display rack constructed in accordance with the present invention.

Fig. 2 is a vertical section thereof taken upon line 2—2 of Fig. 1.

Fig. 3 is a view similar to Fig. 1 of a single storage and display rack constructed in accordance with the present invention, and

Fig. 4 is a vertical section taken upon line 4—4 of Fig. 3.

Referring more in detail to the drawing, the present invention generally consists in the provision of a pair of superimposed shelves upon which magazines may be stored or stacked in piles as respectively indicated at 7 and 7^a, and suitably rigidly secured upon the lower shelf 5 adjacent to but spaced rearwardly from the forward edge of the latter is a longitudinal rest strip 8 which may have a scalloped upper edge as shown in Figures 1 and 3, or be otherwise formed for ornamental purposes. The rest strip 8 extends at an upward and rearward slight inclination and the forward edge of the upper shelf 6 is beveled at a corresponding inclination as well

as formed of lesser depth than the shelf 5

so that the outer surface of the rest strip 8 and the beveled edge 9 of the shelf 6 are in the same inclined plane. It is thus apparent that when copies of the books or magazines are placed on edge so as to seat upon the shelf 5 forwardly of the rest strip 8, they will also be supported in a slightly rearwardly tilted position as shown in Fig. 2 by resting against the strip 8 and the beveled front edge 9 of the shelf 6.

In order to prevent accidental displacement of the copies of magazines or books thus supported for display purposes, off of the rack, a relatively narrow stop strip 10 is rigidly fastened upon the lower shelf 5 along the edge portion of the latter and in spaced relation to and in front of the rest strip 8 so that the lower ends of the displayed copies will be seated between the strips 8 and 10 as shown. The space between the strips 8 and 10 is preferably such as to accommodate two copies of the magazines or books therein, so that a copy from each of the piles 7 and 7^a may be displayed directly in front of said piles where the piles respectively contain different kinds or issues of magazines or books therein.

As shown in Figures 3 and 4 the shelves may be divided into compartments by vertical partitions 11 so that the copies of each pile 8^a may be effectively kept separate from those of the adjacent pile or piles.

In the preferred construction the rack is provided with a horizontal top wall 12 having a beveled front edge 13 in the same inclined plane as the rest strip 8 and the beveled edge 9 of shelf 6, whereby the displayed copies of the magazines or books will also be effectively supported by resting against the beveled edge 13 as clearly shown in Fig. 2. Obviously, the present rack may be embodied in a single structure involving only two superimposed shelves, or may be embodied in a plurality of superimposed cooperating pairs of shelves to provide a multiple rack as in Figs. 1 and 2. In either instance, the rack preferably includes a rear wall 14 and side or end walls 15 so that a rigid and durable structure is had in which the shelves are effectively mounted.

From the foregoing description it is believed that the construction and manner of use as well as the advantages of the present invention will be readily understood and appreciated by those skilled in the art.

Minor changes may be made without de-

parting from the spirit and scope of the invention as claimed.

What I claim as new is:—

5 An open front storage and display rack for magazines or the like including a lower shelf having a rigid stop strip along its forward edge portion and a rigid upwardly and rearwardly inclined rest strip spaced rearwardly from and parallel with said stop strip, and an upper shelf having its forward edge disposed to cooperate with the rest strip to support copies of the magazines, or the like, in an upwardly and rearwardly inclined position for

display when the lower edge portions of said copies are seated between said stop and rest strips, said shelves being adapted to have piles of said magazines stored thereon behind the displayed copies, and a top wall having its forward edge engageable by the upper ends of the displayed copies to aid the upper shelf 15 in supporting said copies in flat condition, said forward edges of the upper shelf and top wall being beveled and in the same inclined plane as the front surface of the rest strip. 20

In testimony whereof I affix my signature.
ALBERT MISRACHI.
